UNITED STATES PATENT OFFICE.

STUART J. BEEBE, OF RICHMOND, INDIANA

GLOVE.

Application filed November 30, 1923. Serial No. 677,777.

My said invention relates to an improvement in gloves and it is an object of the same to provide a glove which can be made from a relatively small number of parts thereby dispensing with a large amount of unnecessary cutting and sewing, in addition to which there will be a smaller number of seams in the completed product.

Another object of the invention is to provide a glove with the fullness at the front instead of the back of the fingers.

Referring to the accompanying drawings, which are made a part hereof and on which similar reference characters indicate similar parts,

Figure 1 is a plan of my improved glove prior to attachment of a finger blank and before joining the same along one side,

Figure 2, a similar view of the blank constituting the inner side of each of two fingers,

Figure 3, a similar view of the glove blank after the part shown in Figure 2 has been attached thereto,

Figure 4, a similar view with the finger piece of Figure 2 spread out,

Figure 5, a perspective of the completed glove, and

Figure 6, a section on line 6—6 of Figure 5.

In the drawings reference character 10 indicates the wrist piece of a glove or gauntlet which may be of any stiff material such as buckram. The wrist piece in the form here shown has attached thereto a piece 11 covering the back of the hand which piece may be made of flannel or canvas or other convenient material and a piece 12 preferably of leather covering the palm 40 of the hand. This piece 12 is slit at 22 and has extensions 13 and 14 for covering the front of the index and little fingers respectively while the portion of each 13 and 14 adjacent the slit 22 is folded around the inner side of the respective finger. The piece 12 is further provided with an opening formed by the cutting out of the piece 16 for the inside of the thumb and into which is set the piece 15 constituting the covering 50 for the back of the thumb.

By means of seams at 17 and 18 I attach to the parts 11 and 12 a strip of material, preferably leather, which is divided by longitudinal cuts into a plurality of strips 19 of unequal length which strips serve for covering the backs of the fingers and which

are integrally united at the upper end as may be seen in Figure 5.

The piece 20, shown in Figure 2, is now secured to the glove blank by spreading it apart and sewing the edge indicated at 21 to the edges of the blank indicated at 22 (Fig. 1) in the form shown in Figure 3. After this the blank may be spread out in the manner indicated in Figure 4, the blank 65 20 now forming the strips 23 and 24 for covering the front sides of the middle and ring fingers.

After this is done the blank may be folded over and stitched wrong side out along 70 its outer edges thus securing the outer edge of the coverings 12 and 13 for the inside of the palm and little finger to the corresponding outer edge of the coverings 11 and 19 for the back of the hand and little finger. 75 The inside and end adjoining edges of the coverings for the little and fore-fingers are next stitched and the side edges of the second and third fingers thus forming the completed glove. The structure of the fingers 80 is indicated in Figure 6 where 19 indicates the narrow back strip of the finger and 14 the wide front strip whereby the fullness of the finger is provided at the front instead of the rear.

Various modifications of my invention will be obvious to those skilled in the art without departing from the spirit of the invention and therefore I do not limit myself to what is shown in the drawings and described in the specification, but only as indicated in the appended claim.

Having thus fully described my said invention, what I claim as new and desire to secure by Letters Patent, is:

A glove comprising an integral leather blank covering the palm of the hand and the first and last fingers, a leather blank secured thereto for covering the two intermediate fingers at their front side, a fabric covering for the back of the hand extending from the wrist to a point adjacent the knuckles and having a substantially straight upper edge, and a set of integral narrow strips of leather secured thereto for covering the 100 backs of the fingers, substantially as set forth.

In witness whereof, I have hereunto set my hand and seal at Richmond, Indiana, this 14th day of November, A. D. nineteen 110 hundred and twenty-three.

S. J. BEEBE. [L. S.]
